REFRIGERATING APPARATUS

Lawrence E. Carson, Alhambra, Calif.

Application January 18, 1947, Serial No. 722,791

20 Claims. (Cl. 62—102)

1

The present invention relates to a refrigerating apparatus and method, and more particularly to apparatus and methods for controlling the temperature and humidity conditions of one or more chambers of a refrigerating apparatus.

This application is a continuation in part of my co-pending application Serial No. 699,797, filed September 27, 1946, which matured into Patent No. 2,539,813 on January 30, 1951, and which embodies apparatus and method for automatically defrosting the refrigeration coils of a low temperature refrigerator while preventing the transfer of heat generated in the defrosting operation to the low temperature storage compartment along an unobstructed path. Means comprising a hooded coil housing are therein provided to trap the air heated in the area of the coils during the defrosting operation, while leaving an open space below the level of the coils for the circulation of cold air, preferably by forced draft, along a duct system to the low temperature storage compartment and back to the hooded coil housing.

The instant invention utilizes all of the structure embodied in the invention of the co-pending application, but, additionally, incorporates one or more high temperature storage compartments adapted to be maintained at a temperature considerably below normal room temperature, but in excess of the temperature of the freezing point of water. These compartments are located in the same cabinet as the low temperature compartment, suitable insulation being provided therebetween.

One of the objects of the instant invention is to provide means whereby the temperature of the high temperature compartment may be controlled.

Another object of the instant invention is to provide means whereby the humidity of the high temperature compartment may be controlled.

A further object of the invention is to provide means whereby the temperature and humidity of the high temperature compartment may be controlled by a control of a diverted portion of the low temperature airstream normally circulated between the refrigeration coil and the low temperature storage compartment.

The foregoing together with other objects and advantages of the invention are preferably accomplished by providing a medially and longitudinally partitioned duct in juxtaposition to a substantial portion of the wall area of the high temperature compartment, and passing through said duct a portion of the low temperature air

issuing from the hooded coil housing. Dampers are provided which may be manually adjusted to control the amount of air passing into the duct, and, also, to control the refrigerating effect of said air on the high temperature compartments by blocking or partially blocking either of the passages of the duct to divert the air from one passage to the other, thus varying the velocity of the duct air and its proximity to the compartments to vary the refrigerating effect. The air issues from the control duct into the air stream passing from the low temperature compartment to the coil housing. Thus, no portion of the temperature and humidity control air for the high temperature compartment passes through the low temperature compartment.

A suitable porous disc in the wall of each of the high temperature compartments provides for water vapor communication between the interior of each compartment and the diverted air stream, thus enabling a substantial control of the humidity of the air in the compartments.

Other objects and advantages of the invention will be apparent from the following description taken in conjunction with the drawings forming part of this specification and in which:

Figure 1 is a sectional view in side elevation of a refrigerator embodying the invention;

figuration of the secondary duct system in solid outline; and

Figure 11 is a schematic view showing the positioned relationship between the various compartments of the apparatus.

Referring to the drawings for more specific details of the invention, the refrigerator is comprised of a storage assembly, a duct assembly, and a hooded coil housing, indicated generally at 10, 12 and 14, respectively. Each wall of the storage assembly is comprised of an inner shell 16, an outer shell 18, and a substantial thickness of insulating material 19, such as glass wool, therebetween. An insulating partition wall 20 is shown as separating a low temperature storage compartment 22 from an auxiliary high temperature storage compartment 24 therebeneath, while another insulating partition wall 26 separates the compartment 22 from a utility high temperature storage compartment 28 located to one side thereof and at substantially the same height in the assembly 10. A thin partition wall 27 shown in Figure 4 separates the compartment 28 from another high temperature storage compartment 29 located therebeneath. Access to the compartment 22 is had through a door 30 located in the top of the assembly and pivotally secured thereto by hinges 32, while access to the auxiliary compartment is had through a door 34 in the front wall of the assembly 10. A door 36 secured to said front wall by hinges 38 provides access to the utility compartments 28 and 29.

The compartment 22 has a floor 40, and above said floor, in spaced relation therewith, is a partition 41 equal in area to said floor, said partition having an imperforate portion 43 and a portion 44 having a plurality of spaced apertures 45 providing for communication between the space between the floor 40 and partition 41 and the chamber 22 thereabove. A baffle 47 separates the imperforate portion 43 of the partition 41 from the perforated portion 44 of said partition, said baffle extending transversely of the chamber 22, as indicated in Figures 1 and 2.

The rear wall of the storage assembly adjacent the low temperature compartment 22 contains a pair of spaced apart vertical ducts 46 and 48, duct 46 having an inlet 50, communicating with the chamber 22 above the partition 41 and with the space between the floor 40 and the partition 41, and an outlet 52 communicating with the duct assembly 12, and duct 48 having an outlet 54, communicating with the chamber 22 above the partition 41 and with the space between the floor 40 and the partition 41, and an inlet 56. Also contained within the rear wall of the storage assembly adjacent the utility compartment 28 is a duct mouth 58 having a baffle 60 extending downwardly from the roof thereof, a baffle 62 spaced therefrom extending upwardly from the floor thereof, and a rubber damper 64, extending the height of the duct mouth, having one edge secured to the duct wall, as by studs 66 and having the other edge secured to a control lever 68 slidable in the wall of chamber 28.

Communicating with the duct mouth 58 is a duct 70 divided, not necessarily centrally, to form two adjacent passages by a partition 72 secured at each end by a cap strip 74 affixed to ribs 76 of the assembly wall. The duct 70 is provided with a venturi 75 and comprises the following inter-communicating sections: section 70A, extending horizontally along the upper rear wall of compartment 28; section 70B, extending along the side wall of compartment 28; section 70C,

extending downwardly from section 70B to section 70D, located along the side wall of compartment 29; section 70E, extending horizontally along the rear wall of compartment 29 and compartment 24, located below the low temperature compartment 22; and section 70F, extending from section 70E toward the housing 14 and having a mouth 73 communicating with the duct 98, hereinafter described. An interconnecting duct 77 is provided for communication between the portions 70A and 70E of duct 70, as shown in Figure 3, said duct passing into portion 70A at the venturi 75.

Partially sheathed rubber dampers 78 and 80 located centrally of the duct section 70A in normal alignment with the duct partition 72, as shown in Figures 4 and 5, are pivotably supported on rods 82 having looped crank arms 84 adapted to be engaged by crank arm 86 of rods 88 journaled for support in trunnions 90 secured within the wall of the assembly, as shown in Figure 6. The rods 88 are adapted to be pivoted by control knobs 91 inset in the jamb of the door 36 to control the dampers 78 and 80.

The portion 70A of duct 70 to the rear of compartment 28 is separated from compartment 28 by an insulation wall 92, as indicated in Figures 2 and 4, while the portion 70B of duct 70 above the damper 78 is separated from compartment 28 by a thin insulation wall 93 of varied thickness, said wall 93, as indicated in Figure 3, being of greatest thickness adjacent the upper end of the duct section 70B and of least thickness at a point immediately above the damper 78.

Porous discs 94 and 96 inserted in the walls of compartments 28 and 29 provide for water vapor communication with the duct sections 70C and D, respectively. These discs are provided to control the humidity within the compartments 28 and 29, as will hereinafter appear.

The duct assembly 12 comprises insulation walls similar in type to those of the storage assembly 10 and is secured to the storage assembly so that the outlet 52 of duct 46 and the inlet 56 of duct 48 are in communication, respectively, with spaced apart vertical ducts 98 and 100 within the duct assembly 12. The duct 98 has an outlet 102 and the duct 100 has an inlet 104, both the outlet 102 and the inlet 104 being provided with inwardly extending flanges, as shown.

The hooded coil housing 14, shown in greatest detail in Figure 9, is rectangular in form and comprises side walls 106 and 108, top and bottom walls 110 and 112, and front and rear walls 114 and 116. In the upper portion of the housing there is supported between the side walls 106 and 108 a refrigerant coil assembly, indicated generally at 118, comprising headers 120, a bank of tubes 122, and a plurality of spaced apart parallel fins 124. A metal drainage tray 126 having a pipe drain 128 underlies the coil assembly 118, and a heater element 127 is located within the housing adjacent the coil assembly. A vertical inner wall 130 and a horizontal inner wall 132, extending from the front wall 114 and terminating a substantial distance forwardly of the rear wall 116 define an air inlet duct having a flanged inlet 134, while an L-shaped baffle 136 extends from the tray 126 to the inner wall 132 above the inlet 134 and from the tray 126 to the bottom wall 112.

Supported by the wall 106 forwardly and below the coil assembly 118 is a rotary blower 138 adapted to be driven by a motor located within a housing 140 supported on the outside of the

housing 14 on the side wall 106. The blower comprises an inlet 142, a blower fan, not shown, and an outlet duct 144 communicating with a flanged outlet 146 of the housing 14.

The hooded coil housing 14 is secured to the duct assembly 12 so that the flanged inlet 134 and the flanged outlet 146 of the housing are received, respectively, by the flanged outlet 102 of the duct 98 and the flanged inlet 104 of the duct 100.

The wiring circuit of Figure 8 shows the manner in which the actuating mechanism of the refrigerator is operably interconnected to provide for a fully automatic cycle of operation. In Figure 8, a compressor motor 148, adapted to circulate a suitable refrigerant through the coil assembly 118, is connected across electrical power lines 150 and 152, while, in shunt therewith, is a motor 154, located within the housing 140 and adapted to drive the fan of blower 138, and a thermostat switch 156. The heater element 127 is connected from line 150 to a pole of a defrost thermostat switch 160. The switches 156 and 160 are shown in position for positive low temperature operation of the refrigerator, and a main thermostat switch 161 is provided between switch 160 and the compressor motor 148. A switch 158 actuated by the door 30 of the low temperature compartment 22 is also provided in the circuit. When the compressor motor 148 and the blower motor 154 are in operation, air at a temperature of from 0-13° F. is recirculated between the hooded coil housing 14 and the storage compartment 22 in the following manner: The air, after passing over the coil assembly 118, passes into the blower inlet 142, along the blower duct 144, upwardly through duct 100 in assembly 12, and downwardly through duct 48 where a portion of the air stream passes into the mouth 58 of duct 70. The remainder of the air stream passes through the outlet 54 so that a portion thereof issues directly into chamber 22 above the partition 41 and the remainder passes between floor 40 of said chamber and the partition 41, said latter portion passing upwardly into the chamber 22 through the apertures 45 in the portion 44 of the partition 41. Due to the increased velocity of the air passing through the holes 45 and the consequent enhanced refrigerative effect of said air, articles stored in that part of the chamber 22 to the left of baffle 47, as viewed in Figures 1 and 2, and above the apertures 45 are given a quick initial freeze, following which they may be removed to that portion of chamber 22 to the right of the baffle 47 for storage. The air at a temperature of 0-13° F. passes out of the compartment 22 through the duct inlet 50, upwardly through duct 46, downwardly through duct 98, and through the duct 134 in the housing 14 to the coil assembly 118. The dotted arrows of Figure 1 indicate the path of air from the blower 138 to the compartment 22 while the solid arrows indicate the path of the air in passing from the compartment 22 to the blower 138.

That portion of the air entering the mouth 58 of the duct 70 may be controlled in amount by a manual adjusting of the damper 64 by means of the control lever 68. Normally, a portion of the volume of air which passes damper 64 passes into the duct 70 on each side of the partition 72. The air travels within duct sections 70A and 70B along the upper rear wall of chamber 28 and the upper side wall thereof, respectively, passes downwardly through sections 70C and 70D along the side wall of chamber 29, and is redirected in sec-

tion 70E along the rear wall of chamber 29 and the rear wall of chamber 24 to issue from a duct outlet 73 into the vertical duct 98 where it rejoins the air stream passing into the hooded coil housing 14.

The air, in passing through the duct 70, serves to withdraw heat from the compartments 24, 28 and 29 through the thin duct wall, and this heat is surrendered to the coil 118. It will be noted that the amount of heat withdrawn from the compartments in this manner may be varied over a wide range to maintain the compartments at a desired temperature. The damper 64 may be manually positioned to prevent the entrance of air to duct 70 or to allow any amount of air to enter said duct up to a maximum volume. When the air passing through duct 70 reaches section 70C, that portion of the duct containing the dampers 78 and 80, it may be subjected to a further measure of control to regulate the temperatures of either of the compartments 28 and 29 without affecting the other compartment. The temperature of compartment 28 is controllable principally by damper 78. By rotating damper 78 in a clockwise direction, as viewed in Figure 5, all of the moving air in duct 70 will be diverted to the right partition 72 away from the wall of compartment 28, thus reducing the refrigerative effect of the air stream. Upon reaching the pivoted damper 78, the air stream will resume its travel on both sides of the partition 72 by passing through the opening in the partition vacated by the pivoting of the damper. When the damper 78 is rotated in a counterclockwise direction, as viewed in Figure 5, the moving air stream is diverted to the left of the partition 72, thus increasing the refrigerative effect of the air stream due to the proximity of the air to the wall of compartment 28 and the increased velocity of the air.

After reaching damper 78 the air stream is redistributed to pass through the opening of the partition vacated by the damper. It is thus seen that a rotation of damper 78 in either direction does not effect a change in the temperature of compartment 29.

Similarly, the rotation of damper 80 in either direction does not affect the temperature of compartment 28. When the damper 80 is rotated in a clockwise direction, as viewed in Figure 5, the moving air stream is diverted to the left of the partition 72 adjacent the wall of compartment 29 to provide an enhanced cooling of the compartment due to the proximity of the air stream and its increased velocity. When rotated in a counterclockwise direction, the damper 80 diverts the air stream to the right of partition 72 to reduce the cooling effect of the air stream on compartment 29.

The relative humidity in compartments 28 and 29 is controlled by means of the porous discs 94 and 96 inset in the compartment walls to provide for communication between the compartments and duct 70. Each of the compartments 28 and 29 has but one porous disc, disc 94 being located at the suction side of damper 78 above the partition 27 and disc 96 being located at the suction side of damper 80, as indicated in Figure 4. The plurality of minute passages through the discs 94 and 96 are capillary in nature. Thus, as moving air stream of relatively low temperature and consequent low moisture content passes the porous discs, a water vapor partial pressure differential exists between the compartments 28 and 29 and the duct 70. The water vapor on the high pressure or

compartment side of the discs is diffused through the discs into the air stream in duct 70 to lower the relative humidity in the compartments. There is no movement of the air mass in the compartments through the discs, as this water vapor transfer takes place, because the porosity of the discs is such as to prevent any passage of air therethrough.

The tapered insulation 93 between the duct section 70B and compartment 28 serves to equalize the temperature of the compartment wall adjacent the duct in the temperature control area of damper 78. The insulation 93 is thickest at the upper end of the side wall of compartment 28 where the temperature of the air stream is at its lowest value in the control area, and the insulation is decreased in thickness toward the damper 78 in approximate proportion to the rise in temperature of the air stream.

As the air stream enters the Venturi throat 75 in the duct 70, the pressure of the stream is decreased in proportion to a velocity increase, said decrease in pressure serving to allow higher pressure air from the lower reaches of duct 70, i. e., section 70E to enter the Venturi throat through the interconnecting duct 71. The air passing through the duct 71 is at a higher temperature than the air in the forepart of duct 70, i. e., section 70A, and, thus, it is seen that the duct 71, the Venturi throat 75, and the tapered insulation 93 serve to equalize the temperature of the compartment walls adjacent the duct 70. In this manner, extremes of temperature between portions of the walls of compartment 28 and portions of the walls of compartment 29 are prevented, and the possibility of the zero degree air frosting the walls is obviated. A damper, or other control means, may be provided in duct 71 to control the amount of air recycled between duct sections 70E and 70A.

The metering of the air into the secondary duct system 70 by means of the damper control 64 to restrict the diverted or secondary air stream to a comparatively small percentage of the total air stream in the primary duct system, together with the recycling of the air in the secondary duct system by means of duct 71 and venturi 75, insures that the air passing through the temperature and humidity control region, section 70C, of the secondary duct system will be at a temperature of 32° F. or above, corresponding to the desired temperature range of the high temperature storage compartments 28 and 29.

As the aforescribed operation continues, heat from the circulating air is being continuously given up to the refrigerant within the coil assembly 118 to lower the temperature of the circulating air, and frost is being continuously formed on the coil assembly in this process.

When the temperature of the air in the low temperature compartment has dropped to a lower limit value, as for example zero degrees F., the main thermostatic switch 161, located within the compartment 22 automatically opens in response to the temperature in compartment 22 to disconnect the compressor motor 148 and the blower motor 154 from the power source. When the temperature of compartment 22 rises to approximately 5°, the switch 161 closes to actuate the motors 148 and 154. This operation is continuous until the frost formed on the coil 118 is sufficient to restrict the flow of air through the coil. When the air is restricted and the fins 124 of the coil 118 are partially insulated with a film of frost, the effect is produced of re-

ducing the refrigeration load on the coil. When the refrigeration load is reduced, the coil temperature is lowered to a point below its normal temperature corresponding to the equivalent temperature of compartment 22. When the coil temperature is thus reduced, the defrost switch 160, located within the housing 14, automatically reverses to disconnect the compressor motor 148 and the blower motor 154 from the power source and to connect heater element 127, also located within the housing 14 adjacent the coil assembly 118, to said source. When the air in the vicinity of the coil assembly reaches a temperature of approximately 15° F., the thermostat switch 156 opens. The air within the upper portion of housing 14 is continually heated by the heater element 127 until it reaches a temperature of approximately 38° F. in order to completely defrost the coil assembly 118. As the temperature of the air rises and the defrosting operation continues, water falls from the coil assembly 118, collects in the tray 126, and passes therefrom through the drainpipe 128 to a location, not shown, outside of the housing 14.

It will be noted that the warm air, of a temperature approaching 38° F., within the housing 14, is prevented from entering the storage compartment 22 and the duct 70 or from causing any substantial temperature raising effect in said compartment and duct by virtue of the warm air trap provided in the housing 14 above the blower 138, and the fact that the warm air will have to extend downwardly to the duct 134 in order to pass into the vertical duct 98, for the air may not freely pass through the blower 138 into duct 100 when the blower fan is not in operation. Thus, there will be relatively little heat transfer due to convection between the housing 14 and the ducts 98 and 100. There will be heat transfer by way of conduction, however, between the warm air at 38° F. in the upper portion of the housing 14 and the cold air in ducts 98 and 100, but as the air in these ducts is raised in temperature, it will rise to be trapped in the upper portion of ducts 46 and 48, and will be prevented from passing into the storage compartment 22 by the downwardly extending baffle-like insulation wall of the assembly 10, and from passing into the duct 70 by the downwardly extending baffle 60 in the duct mouth 58. Additionally, it will be noted that the disposition of the low temperature compartment inlet 54 with respect to the secondary duct inlet 58, and, also, the configuration of the heat loop baffle system comprising baffles 60 and 62 within the mouth of the secondary duct 70 cooperatively prevent the passage of low temperature air from the low temperature compartment to the high temperature compartment duct system during periods of inactivity of the blower 138, thus preventing the lowering of temperatures of the high temperature compartments below 32° F.

At the completion of the defrosting operation, therefore, the temperature of the still air in compartment 22 is only slightly raised from its temperature previous to the defrosting operation, and the temperature of the still air in the high temperature compartments is not lowered below 32° F.

When the temperature of the air within the housing 14 reaches 38° F., the defrost thermostat switch 160 again automatically reverses to disconnect the heater element 127 and actuate the compressor motor 148. It is to be noted that the thermostat switch 156 is in the open position and the blower motor 154 is not in operation. The

temperature of the air within the housing 14 drops under the cooling action of the refrigerant within the coil assembly 118, and, when the temperature of the air has dropped from 38° F. to approximately 13° F., the thermostat switch 156 closes to actuate the blower motor 154 to cause circulation of the air between the housing 14 and the storage compartment 22 and duct 70 along the closed paths heretofore described. When the air again reaches a temperature of approximately zero degrees F., the main thermostat switch 161 cycles the operation of condenser motor 148 and blower motor 154 until ice is again sufficiently accumulated on the fins 124 to restrict the flow of air therebetween.

When the door 30 of the low temperature compartment 22 is opened, the switch 158 is opened thereby to disconnect the motors 148 and 154. The closing of the door closes this switch to re-actuate said motors.

While the preferred embodiment of the invention has been shown and described, it is understood that the structure shown is susceptible of modification within the scope of the appended claims.

What I claim as new and desire to secure by Letters Patent is:

1. In refrigerating apparatus, the combination of a chamber to be refrigerated defined at least partially by relatively thin walls, relatively thick insulation walls spaced outwardly therefrom, a refrigerant coil, means for effecting forced draft circulation of air between said coil and the space between said walls to refrigerate said thin walls, and control means within said inter-wall space for varying the refrigeration effect on said thin walls of a specific volume of air so circulated.

2. In refrigerating apparatus, the combination of a chamber to be refrigerated defined at least partially by relatively thin walls, relatively thick insulation walls spaced outwardly therefrom, a refrigerant coil, means for effecting forced draft circulation of air between said coil and the space between said walls to refrigerate said thin walls, means for controlling the volume of air so circulated, and control means within said space for varying the refrigeration effect on said thin walls of said controlled volume of air.

3. In refrigerating apparatus, the combination of a chamber to be refrigerated, a refrigerant coil, means for passing air in forced draft circulation from the coil over the walls of the chamber to refrigerate said walls and thereby said chamber, and means forming a passageway through a wall of said chamber providing for capillary communication between the atmosphere of said chamber and said circulating air, whereby the humidity of said atmosphere may be controlled by the removal of water vapor from said atmosphere into said circulating air through said passageway.

4. In refrigerating apparatus, the combination of a chamber to be refrigerated and a duct system located exteriorly of said chamber and having a wall in common with the chamber, a refrigerant coil, means for passing air in forced draft circulation from the coil to the duct system and therethrough to refrigerate the chamber, means to control the input of air into the duct system, and other means located within said duct system to control the rate of passage through said duct system of the input air passed into said system by said control means and to vary the proximity of the flow of said input air to the wall common to the chamber and the duct system.

5. In refrigerating apparatus, the combination

of a chamber to be refrigerated and a duct system located exteriorly of said chamber and having a wall in common with said chamber, a partition parallel to said common wall to divide the duct system, a refrigerant coil, means for passing air in forced draft circulation from the coil to the duct system and therethrough along both sides of said partition to refrigerate the chamber, means to variably control the input of air into the duct system, and other means located within said duct system to variably control the rate of passage through a portion of the duct system of the input air passed into said system by said control means by diverting air from one side of said partition to the other side of the partition to vary the refrigerative effect of said air on said chamber.

6. In refrigerating apparatus, the combination of a chamber to be refrigerated and a duct system

located exteriorly of said chamber and having a wall in common with said chamber, a partition parallel to said common wall to divide the duct system, a refrigerant coil, means for passing air in forced draft circulation from the coil to the duct system and therethrough along both sides of said partition to refrigerate the chamber, means to variably control the input of air into the duct system, other means to variably control the rate of passage through a portion of the duct system of the input air passed into said system by said control means by selectively directing air from one side of said partition to the other side of the partition to vary the refrigerative effect of said air on said chamber, and means forming capillary passageways in said common wall to provide for the control of the humidity of the air in the chamber by allowing for the passage of water vapor from said chamber into said duct system.

7. In refrigerating apparatus, the combination of a chamber to be refrigerated and a duct system adapted to pass air over the exterior of said chamber to refrigerate the same, a refrigerant coil, means for passing air in forced draft circulation

from the coil to the duct system and therethrough to refrigerate the chamber, and baffle means at the mouth of said duct system adapted to prevent the convective movement of air into and out of the mouth of the duct system due to stratified temperature variation of the air when said air is not in forced draft circulation.

8. In refrigerating apparatus, the combination of a primary chamber and at least one secondary chamber to be refrigerated, a refrigerant coil, a

duct system for conveying forced draft air between said coil and the interior of the primary chamber, another duct system connected into the first duct system and adapted to bypass a portion of the air from the first duct system and

60 direct it exteriorly over the walls of the secondary chamber to refrigerate said chamber, baffle means in the first duct system adapted to prevent cold air from passing out of the primary chamber and warm air from passing into the primary chamber

65 when the air in the duct systems is not in forced circulation, and baffle means in the mouth of the second duct system to prevent the convective movement of air into and out of the mouth of the duct system due to stratified temperature variation of the air when said air is not in forced draft circulation.

9. In refrigerating apparatus, the combination of a chamber to be refrigerated, a partition adjacent to and inwardly spaced from a wall of said chamber to provide therewith a passage, said

partition having a perforate and an imperforate portion, a baffle extending from said partition to subdivide said chamber, said baffle serving to separate the perforate and imperforate portions of the partition, a refrigerant coil, means for introducing a forced draft air stream therefrom directly into that subdivision of the chamber adjacent the imperforate portion of the partition and into said passage to enter the other subdivision of the chamber through the perforate portion of the partition, and means for passing the air in said chamber back to said coil.

10. In refrigerating apparatus, the combination of a low temperature chamber and at least one high temperature chamber to be refrigerated, a refrigerant coil, means forming a passageway for forced draft circulation of air over said coil, into said low temperature chamber, and back to said coil, and means forming a second passageway communicating with said first passageway and adapted to receive air from said first passageway for circulation over walls forming the exterior of said high temperature chamber.

11. In refrigerating apparatus, the combination of a low temperature chamber and at least one high temperature chamber to be refrigerated, a refrigerant coil, means for causing an air stream to flow across said coil, means for dividing said air stream, means for receiving one portion of said stream and causing it to flow into and through the interior of said low temperature chamber, means for receiving the other portion of said stream and causing it to flow across the exterior of said high temperature chamber, and means for rejoining said stream portions and for directing the resultant stream to said coil.

12. In refrigerating apparatus, the combination of a low temperature chamber and at least one high temperature chamber to be refrigerated, a refrigerant coil, means for causing an air stream to flow across said coil, means for dividing said air stream, means for receiving one portion of said stream and causing it to flow into and through the interior of said low temperature chamber, means for receiving the other portion of said stream and causing it to flow across the exterior of said high temperature chamber, means for rejoining said stream portions and for directing the resultant stream to said coil, and control means for the receiving means for said other stream portion adapted for the flow control of said other stream portion.

13. In refrigerating apparatus, the combination of a low temperature chamber and at least one high temperature chamber to be refrigerated, a refrigerant coil, means for causing an air stream to flow across said coil, means for dividing said air stream, means for receiving one portion of said stream and causing it to flow into and through the interior of said low temperature chamber, means for receiving the other portion of said stream and causing it to flow across the exterior of said high temperature chamber, means for rejoining said stream portions and for directing the resultant stream to said coil, control means for receiving means for said other stream portion adapted for the flow control of said other stream portion, and means forming a passageway between the interior of said high temperature chamber and said last mentioned receiving means, said passageway means embodying a plurality of channels of capillary dimensions for the passage out of said chamber and into said other stream portion of water vapor, whereby the humidity of

the atmosphere within said high temperature chamber may be controlled.

14. In refrigerating apparatus, the combination of a low temperature and at least one high temperature chamber to be refrigerated, a refrigerant coil, a first passageway including the interior of said low temperature chamber forming a circuit for the flow of air away from and back to said coil, a second passageway defined in part by the outer surface of the walls of said high temperature chamber having an inlet communication with said first passageway between said coil and low temperature chamber and an outlet communication with said first passageway between said low temperature chamber and said coil, and means for causing a refrigerating air stream to flow across said coil and through said passageways.

15. The combination as set forth in claim 14 wherein valvular means are provided in said second passageway to control the amount of air admitted to said second passageway.

16. The combination as set forth in claim 15 wherein said second passageway has at least a portion thereof divided into parallel sections by a longitudinally extending partition and wherein damper means carried by said partition are operable to intercept the air flow on either side of said partition to control the refrigerative effect on said high temperature chamber of the air passing through said second passageway by controlling the proximity of flow of said air to the wall of said chamber and the velocity of flow.

17. The combination as set forth in claim 14 wherein said second passageway has at least a portion thereof divided into parallel sections by a longitudinally extending partition and wherein damper means carried by said partition are operable to intercept the air flow on either side of said partition to control the refrigerative effect on said high temperature chamber of the air passing through said second passageway by controlling the proximity of flow of said air to the wall of said chamber and the velocity of flow.

18. In refrigeration apparatus embodying a chamber to be refrigerated comprising thin walls, relatively thick insulation walls spaced outwardly therefrom to define therewith a passageway for refrigerating air, a refrigerant coil, and means for effecting the movement of refrigerating air from said coil and through said passageway, the improvement consisting in providing the thin walls of said chamber with a varying effective insulation thickness to decrease the insulating effect of said walls in the direction of flow of said refrigerating air moving past the exterior surfaces thereof, whereby the interior surface portions of said thin walls will have substantially the same temperature due to the juxtaposition, to the exterior wall surface portions of greater insulative thickness, of air of lower temperatures, and, to the exterior wall surfaces of lesser insulative thickness, of air warmed above said lower temperatures by the reception of heat from the wall surfaces.

19. In refrigerating apparatus, the combination of a chamber to be refrigerated and a duct system located exteriorly of said chamber and having a wall in common with the chamber, said duct system having inlet and outlet portions adjacently disposed, a refrigerant coil, means for passing air in forced draft circulation from the coil to the inlet portion of the duct system, means for receiving said air from the outlet portion of the duct system and for directing said air to

the coil, another duct interconnecting the inlet and outlet portions of said duct system, and a Venturi-like restriction in the inlet portion of the duct system located at the mouth of said interconnecting duct.

20. In refrigerating apparatus, the combination of low and high temperature chambers to be refrigerated, a refrigerant coil, first duct means forming a communicating circuit between the region of said coil and the interior of said low temperature chamber, second duct means forming a communicating circuit between the inlet side of said first circuit and the outlet side of said first circuit, and by-passing said low temperature chamber, said second duct means being defined in part by a relatively thin wall forming a wall of the high temperature chamber, means for effecting forced draft circulation of air over said coil and through said first and second duct means, and fixed baffle means located adjacent the inlet 20

of said second duct means operable upon the cessation of said forced draft circulation of air to prevent the passage of low temperature air from said low temperature compartment into 5 said second duct means.

LAWRENCE E. CARSON.
